(57) **CLAIM**

The ornamental design for a cartridge container for extraction, as shown and described.

DESCRIPTION

This application is related to U.S. patent application Ser. No. 29/540,392, filed on Sep. 24, 2015.

FIG. 1 is a perspective view of a cartridge container for extraction showing my new design;

FIG. 2 is another perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a sectional view thereof taken along line 9-9 of FIG. 3;

FIG. 10 is a sectional view thereof taken along line 10-10 of FIG. 3; and,

FIG. 11 is a sectional view thereof taken along line 11-11 of FIG. 7.

1 Claim, 9 Drawing Sheets
